TRIP LATCH FOR PIPE TONGS

Marcus L. Hacker, Beaumont, Tex.

Application October 27, 1930. Serial No. 491,439

16 Claims. (Cl. 81—53)

The invention relates to an improvement in pipe wrenches or tongs, and particularly the type which are used in and about well derricks and pipe lines.

5 Tongs of this type are in common use and usually comprise a handle and a plurality of jaw members which are adapted to encircle the pipe. The tongs now in use involve a latch which is carried by one jaw member and arranged to pass between two outstanding lugs on the other jaw member, so that the jaws will be firmly held about the pipe. In many instances, and particularly in the drilling operations where the pipe sections are to be screwed together, it 10 is desirable to have a tong or wrench which will release from the pipe when a predetermined torque is exerted upon the handle, so that the threads on the pipe sections will not be galled. It is with the object in view of providing a pipe 15 tong or wrench which will release from the pipe when the maximum stress which may be withstood by the threads is approached, that the present invention has been devised. Thus, as the latch releases the tong will be freed from the pipe and injury to the threads will be avoided.

It is one of the objects of the invention to provide a separate and individual latch which may be attached to the pipe tongs which are now in general use.

30 Another object of the invention is to provide a latch which will release the jaw members when a predetermined pressure is exerted upon the jaw by contact with the pipe.

Another object of the invention is to provide 35 a trip-latch having a slidable bolt member which may move to a releasing position.

Still another object of the invention is to provide a trip mechanism which will permit the bolt latch to move to releasing position.

40 It is also an object of the invention to provide a latch the pivot points upon which the parts move will be in substantially a straight line when the latch is closed in combination with means to normally hold them in such position.

45 Still another object of the invention is to provide a spring pressing mechanism which is so associated with the latching device that it will normally resist tripping of the latch until a predetermined pressure is exerted upon the latch.

50 A still further object of the invention is to provide a latch as a separate unit which may readily be attached or detached to various types of pipe tongs which are now in general use.

55 Various other objects of the invention will be readily apparent when the following description

is considered in connection with the accompanying drawings, wherein:

Fig. 1 is a top plan view of the latch mechanism separate from the tong and showing the trip bolt in open position.

Fig. 2 is an elevation similar to Fig. 1, but showing the bolt in retracted or closed position.

Fig. 3 is an end view looking from the lefthand side of Fig. 2.

Fig. 4 is a top plan elevation of a modified form 65 of the invention.

Fig. 5 is a section taken on the line 5—5 of Fig. 4, and looking in the direction of the arrows.

Fig. 6 is a top elevation of one type of well-known tong to which the invention has been 70 applied.

The invention may be readily understood by having reference to Fig. 6 wherein a pipe tong or wrench 1 has been illustrated. These tongs are in general use on the market and comprise 75 a handle 2 and a plurality of jaw members 3 and 4, each of which is made up of a plurality of contact pieces or adapters 5 and 6. These adapters are pivoted together at 7 so that they may encircle the pipe, which is illustrated at 8. A handle 9 is affixed to each of the jaws whereby they may be gripped and drawn about the pipe 80.

Due to the fact that the jaws 3 and 4 are pivoted at different points, such as 10 and 11 on the handle 2, these jaws will clamp about the pipe 85 when the handle is moved in a clockwise direction. The clamping action is caused, due to the pivotal connection therein, and the adapters 5 and 6 will then securely clamp the pipe when the ends 13 and 14 of the jaws are held together. It

is usual to have a horizontal swinging latch member which has an enlarged head thereon. This latch member pivots about the pin 15 so that its head will pass between the lugs 16 which are carried by the jaw member 3. As the tongs were used before the application of my invention this latch member is merely a straight piece of material, and when it is desired to unlatch the tong it is necessary to remove the tension on the handle and slack up the jaw members so that the latch member may be removed from between the lugs 16.

It is understood that there are two of these lugs spaced apart to admit the latch between them, so that the enlarged head of the latch prevents subsequent movement of the lugs 95 so long as the latch is held in position. My invention, however, is arranged to be mounted on the pin 15 and be substituted for the usual latch member.

100 Fig. 6 shows my invention as applied to the 110

105

110

tong wherein the invention is illustrated generally at 20.

By having reference to Figs. 1 and 2 the invention may be best understood, and includes a 5 jaw 21. This jaw is provided with a passage 22 which is arranged to receive the pivot bolt 15. This jaw is formed with a horizontal extending portion 23, which is formed with a groove 24. This groove is dove-tailed in configuration, and 10 arranged to receive the slideable trip latch or bolt 26 which has formed a dove-tailed interfitting portion 27 thereon. This bolt is shown in extended position in Fig. 1 and retracted position in Fig. 2.

15 The bolt 26 has an enlarged head 28 thereon which is wider than the stem 29, so that the head may be received between the upper and lower lugs 16 which are shown in Fig. 6.

In the embodiment of the trip latch shown 20 in Figs. 1, 2, and 3 an ear 30 is formed or connected with the bolt 26 and carries a pivot pin 31. A plurality of links 32 will pivot on this bolt, and upon the pin 33 which is carried by the head 34 of the arm 35. This arm is pivoted at 36 on 25 an ear 37 formed on the body of the latch. This forms a linkage so that movement of the bolt 26 will cause movement of the links 32, and the arm 35, from the open position shown in Fig. 1 to the closed position shown in Fig. 2.

30 It is one of the objects of the invention to provide a resistance to opening for this sliding bolt 26, and to accomplish this a spring pressed pin 40 is provided, which is arranged to slide in the sleeve 41 and is normally held in extended position by a spring 42. This spring abuts against an 35 adjustable plug 43 so that the compression of the spring may be adjusted by movement of this plug so that the pin 40 will be depressed when it is subjected to any definite and predetermined 40 pressure. The arm 35 carries a lug or projection 45 which is arranged to abut against the beveled face 46 on the pin 40. This pin 45 is rounded so that when it tends to move outward away from the bolt 26 its movement is normally resisted by 45 engagement against the face 46, as best seen in Fig. 2. However, when the torque on the handle of the tong is resisted by engagement of the jaws with the pipe to the extent that the pressure is 50 greater than can be withstood by the spring 42 the pin 45 then causes depression of the pin 40 so that the arm 35 will move outward to assume the position shown in Fig. 1. This outward movement of the arm 35 allows the links 32 to move 55 to an extended position which in turn permits the sliding of the bolt 26. It should be noted that the pins 33, 31 and 36 lie in approximately a straight line when the latch is closed so that there is no twisting movement on the parts and the latch will not open until these pins are moved 60 out of alignment.

With the foregoing arrangement of the structure it seems apparent that when a pipe is being screwed into position, that the plug 43 may be 65 adjusted for that particular size of pipe, so that a pressure will be exerted by the tong on the pipe which approximates the pressure at which the pipe sections will be tightly screwed together. When, however, this pressure is exceeded the pin 40 will be depressed and the tong will 70 release its hold upon the pipe so that the threads of the pipe will not be injured by the excessive power and pressure being exerted upon the tong. It is to be understood that the tongs of the type here illustrated are usually manipulated by 75 power about the well derrick and that the oper-

ator is not always able to accurately control the power which is being applied to the tong, so that in many instances the operator is not aware of the exact instance at which the joint is tightly made up, and if power is continued after this instant the threads are injured, or the surface of the pipe is mutilated or in some instances the tong will break; but with my invention of improved latch, when a stress equal to that which should be placed on the joint is reached the tong will automatically release its grip upon the pipe, due to the fact that the bolt or trip latch 26 is permitted to move to releasing position.

80 Figs. 4 and 5 show a modified form of the invention in which the links 32 have been dispensed with, and arm 35 is slightly modified and is shown at 35' as having a curved cam surface 50 which terminates in the nose 51. This cam surface is arranged to contact a roller 52 which is mounted upon a shaft 53. This shaft 53 is carried by the jaw 20 which is identical with the 85 jaw 20 shown in the preceding modification. A stop lug 27' is shown to limit the outward movement of the bolt 26.

90 The spring pressed pin 40 is carried by the sleeve 41 as previously described, and contacts the pin or lug 45 which is carried by the arm 35'. The operation of this entire device is the same as in the preceding figure, except the cam surface and roller have been substituted for the linkage in order to control the movement of the latching bolt 26.

95 In order that the trip latch 20 will not swing out of position but will at all times be retained at a point whereby it may be readily latched, a stop lug 55 has been provided which is formed with a socket 56 which normally receives a spring, the opposite end of which abuts against the jaw 4 of the tong. In this manner as the latch tends to swing outwardly this spring resists the swinging movement and normally retains the latch 105 in a position whereby it may be readily passed about the lug 16.

110 While I have shown and described two forms of the invention it is to be understood that various alterations and modifications may be made thereon, and that various arrangements for controlling the movement of the trip bolt may be devised. It is intended that the latch may be 115 mounted on any type of tong or wrench which is used about pipe, or for other similar purposes. The latch may be readily applied to existing structures, or it may be embodied in the tong when it is originally constructed. It is also intended that the handle 2 may be modified to 120 take on any desired configuration so that it may be used with a makeup or backout post or it may be used in the form illustrated in Fig. 6 of the drawings.

125 Having described my invention what I claim is:

1. A wrench of the character described including jaw members, an automatically releasable latch mounted to connect said jaws, and means on said latch responsive to the pressure tending to open said jaws to release said latch.

130 2. A wrench including a plurality of jaw members adapted to encircle a pipe, a trip latch to couple said jaw members about the pipe, and means holding said latch against release, said means being releasable in response to a predetermined pressure on said jaws.

135 3. A wrench including a plurality of jaw members adapted to encircle a pipe, a trip latch to couple said jaw members about the pipe, and

means to hold said latch to hold said jaws, said means being releasable in response to torque on said wrench.

4. A pipe tong comprising jaws, a handle, and 5 a releasable latch for the jaws, said latch including a slidable bolt, a trip arm arranged to be moved by said bolt, and a pin normally resisting movement of said arm by said bolt.

5. A pipe tong comprising jaws, a handle, and 10 a releasable latch for the jaws, said latch including a slidable bolt, a trip arm arranged to be moved by said bolt, a pin normally resisting movement of said arm by said bolt, and means to adjust the compression on said pin in proportion 15 to the torque to be exerted on said handle.

6. In a pipe tong, horizontal swinging jaws, a horizontal swing latch for said jaws embodying a slidable bolt, and means operable by a predetermined torque on the tong to release said latch.

20 7. An automatically releasable latch for pipe tong having a plurality of jaws including, a body adapted to pivot on one of the tong jaws, a slid- able bolt arranged to engage another jaw, and means carried by said body and adapted to yield- 25 ingly resist movement of said bolt.

30 8. An automatically releasable latch for pipe tongs having a plurality of jaws including, a body adapted to pivot on one of the tong jaws, a slid- able bolt arranged to engage another jaw, and means carried by said body and adapted to yield- 35 ingly resist movement of said bolt, but re- leases at a predetermined pressure.

35 9. An automatically releasable latch for pipe tongs having a plurality of jaws including, a body adapted to pivot on one of the tong jaws, a slid- able bolt arranged to engage another jaw, and means carried by said body and adapted to yield- 40 ingly resist movement of said bolt, and means to adjust the pressure at which said means will release.

40 10. A latch for tongs including a body, an arm pivoted thereto, a bolt slidable with respect to said body, and interengaging means on said arm and body to resist movement of said bolt until 45 a predetermined pressure has been exerted.

11. A latch for tongs including a body, an arm pivoted thereto, a bolt slidable with respect to said body, and interengaging means on said

arm and body to resist movement of said bolt until a predetermined pressure has been exerted, whereupon said means will release said bolt.

12. A latch for wrenches including three pivot pins, links connecting said pins so that when 80 said latch is in position to retain the wrench in pipe engaging position the three pivot pins ap- proximately approach a straight line joining the two end pins, and a movable bolt to resist movement of the center one of said pins from 85 the approximate straight line.

13. A trip latch including three pivot pins dis- 90 posed in approximate alignment when the latch is closed, means to normally resist movement of one of said pins from approximate alignment, but adapted to release such pin upon applica- 95 tion of a predetermined pressure thereto.

14. A latch of the character described includ- 100 ing a linkage operable to release the latch by a force acting in such direction as to have a com- ponent longitudinally of and also transversely to said linkage, means to normally retain said linkage in approximately aligned position when said latch is closed, said means being so disposed with respect to said linkage that only the trans- 105 verse component of the force being resisted need be exerted to retain the pivot pins in approxi- mate alignment.

15. A latch including a three point linkage, 110 three pivot pins in said linkage adapted to ap- proximate the same straight line when the latch is closed and to move out of approximate alignment when the latch moves to open position, and releasable means to resist the opening of the latch by retaining one of said pins in approximate alignment.

16. A latch including a three point linkage, 115 three pivot pins in said linkage adapted to lie on approximately a straight line joining the two end pins when the latch is closed, said pins being adapted to move out of alignment when the latch moves to open position, and means to resist movement of one of said pins with a force at least equal to a second force which is the complement of the force necessary to retain the 120 pivot pins in approximately aligned position against the torque exerted on the latch.
